UNITED STATES PATENT OFFICE.

JACOB KOHN, OF NEW YORK, N. Y.

CLOSING AND LOCKING DEVICE FOR SLIDING DOORS.

1,094,900.

Specification of Letters Patent.

Patented Apr. 28, 1914.

Application filed October 22, 1913. Serial No. 796,658.

To all whom it may concern:

Be it known that I, JACOB KOHN, a subject of the King of Hungary, and resident of the city of New York, in the county of New York and State of New York, have invented certain new and useful Improvements in Closing and Locking Devices for Sliding Doors, of which the following is a specification.

10 The present invention relates to sliding-door closing and locking devices, and is specially adapted for use in connection with the doors leading to elevator shafts and the like, although not limited to that use.

15 The main object of the present invention is to provide a simple, inexpensive and efficient lock for a sliding door, said lock coöperating with a device for moving the said door to closing position, means being provided in said lock for holding said last named device, at will, against closing movement.

20 Another object of the invention is to provide a device of this character which can be manufactured on a commercial scale, or in other words one which is not so difficult to produce as to be beyond the reasonable cost of such an article.

25 With these and other objects in view, which will more fully appear as the nature of the invention is better understood, the same consists in the combination, arrangement and construction of parts hereinafter fully described, pointed out in the appended 30 claims and illustrated in the accompanying drawings, it being understood that many changes may be made in the size and proportion of the several parts and details of construction within the scope of the appended 35 claims without departing from the spirit or sacrificing any of the advantages of the invention.

40 Two of the many possible embodiments of the invention are illustrated in the accompanying drawings, in which:—

45 Figure 1 is a view in elevation of the sliding door of an elevator shaft with the device of the present invention applied thereto, the view being taken from the inner or car-side 50 of the elevator shaft and the door being in its closed position; Fig. 2 is an enlarged front elevation of the lock with the parts in their closing positions, its cover being removed to more clearly show the interior construction; Fig. 3 is a similar elevation of the lock with the parts in different positions;

Fig. 4 is a horizontal section taken through the means which moves the door to its closing position; Fig. 5 is a plan view of this means; Fig. 6 is a side elevation thereof; 60 Fig. 7 is a section taken through a detail of construction; Fig. 8 is a fragmentary view in elevation of a sliding door equipped with a modification of the invention; and Fig. 9 is a horizontal section taken through a modified means for shifting the door toward and 65 into closing position.

Referring now more particularly to Figs. 1 to 7, inclusive, the numeral 10 indicates the sliding-door of an elevator shaft, which 70 together with a stationary door 11 extends substantially throughout the width of the opening of the elevator shaft, the door 11 being hinged at 12, 12 to the door frame, thereby permitting both doors to be swung 75 outwardly as a whole so as to permit large objects to be loaded upon and to be taken from the elevator car. The locking and closing mechanism of the door is applied to the inner or car-side of the door. The 80 lock comprises a casing 13, that is attached by screws, or otherwise, to the sliding-door, and contains a catch 14, in the form of a dog, that is pivoted at 15 to the casing, and provided near its lower free end with a horizontal extension 16, having a rounded edge 17 for a purpose hereinafter to be described. A spring 18 bears against one end of the casing and the catch, and tends to force the latter toward the front edge of the lock 90 casing. A catch actuating lever 19 is fulcrumed at 19' to the lock casing, one of its arms, denoted by the numeral 20, being adapted to contact with the said catch, while its other arm, denoted by the numeral 21, extends through an aperture 22 in the lock casing out of the latter, where it is connected with an operating rod 23, that projects through a guide 24 and extends throughout the width of the door. The arm 20 of the 100 catch actuating lever carries a lug 25, to which is fastened one end of a spring 26, the other end of which is secured to a stop 27. This spring tends to draw the lug 25 into contact with the peripheral face of a 105 disk tumbler 28, that turns around a pivot 29. The tumbler is provided with a substantially triangular notch 30, adapted to co-operate with the door closing means herein-after to be described, and with a notch 31, 110 into which the lug 25 abovementioned is seated when the said tumbler is shifted

around its pivot in a manner hereinafter to be specified. The stop 27 is disposed within a recess 32 in the said tumbler, the edge 33 of said recess bearing against said stop when the parts of the lock mechanism occupy the positions shown in Fig. 2 of the drawings, in which the door is in its closed position. In its front and upper edges the lock casing is provided with an opening 34, through which extends into the same a link 35, that is fulcrumed at 36 to the lock casting, its inner wedge-shaped end 37 engaging the horizontal extension 16 of the catch 14 when the door is closed, and the notch 30 in the disk tumbler 28 when the door is open. The outer end of the link 35 is connected with one end of a link 38 by the intermediary of a door closing device presently to be described. The other end of the link 38 is pivoted at 39 to a bracket 40, that is attached to the stationary door 11. The door closing mechanism, which connects the links 35 and 38, comprises, broadly speaking, a spring or other suitable means for causing a swinging motion of said two links. Means may be provided, for instance in the form of a check, which prevents the slamming of the door. Before proceeding to describe the door closing means in detail, it is to be observed that any suitable door check and closer connecting the links 35 and 38 may be made use of, the one herein described being shown for purposes of illustration only.

With reference to Figs. 4 to 6, inclusive, the numeral 41 designates a casing, comprising a spring chamber 42 and a liquid chamber 43. The spring chamber is provided with a slot 44, through which is inserted into the same the inner end of the link 38, the latter being attached to said casing by rivets 45 and screws 45', or in any other suitable manner. The outer end of the link 35 is also adapted to be inserted through the slot 44 into the said spring chamber and to move freely within a slot 46, that extends in a plane at right angles to that of the slot 44. The end of the link 35, which is disposed within the spring chamber 42, is provided with a square hole 47, in which is seated the squared portion 48 of a shaft 49, which extends through the spring chamber into the liquid chamber, as clearly shown in Fig. 4 of the drawings.

The numeral 50 designates a sleeve, having a groove 51 formed in its side, and provided upon its upper end with a ratchet wheel 52, that is engaged by a pawl 53, which is pivoted to the link 35. The inner end of a spiral spring 54 in the spring-chamber is hook-shaped, and is seated in the groove 51 in the sleeve 50, the other end of said spring being attached to the side of the spring chamber. In the liquid chamber is disposed a piston 55, that is connected by the intermediary of a pitman 56 with a

crank 57, which is attached to the lower end of the shaft 49. The piston is provided with a port 58 in its front end, controlled by a valve 59, an aperture 60 being provided in the rear end of the piston. The spaces in front and rear of the piston are adapted to communicate through a passage 61, which is controlled by a valve 62, to govern the flow of the liquid and the extent of the resistance of the same to the door closing operation of the spring 54. Suitable packing means 62' are provided for preventing the passage of the liquid from the liquid chamber into the spring chamber. The spring chamber is closed by a cover 63, which is provided with an extension 64, covering the slot 44 in the spring chamber. To prevent friction between the link 35 and the spring, a washer 65 is disposed between the spring and said link. By turning the ratchet 52 by means of a key, the initial force of the spring 54 may be regulated as desired, and it will be seen that the force of the said spring always tends to turn the link 35 in the direction of the arrow indicated in Fig. 1 of the drawings, that is to say away from the link 38. The movement of the door closing means, which as above described is attached to the link 38, is guided by a plate 66, that is attached to the inner face of the stationary door 11, and provided with an arc-shaped slot 67, into which projects a lug 68, that is carried by the casing 41.

When the sliding-door is in its closed position, the links 35 and 38 are in the positions shown in Fig. 1 of the drawings, in which the inner wedge-shaped end 37 of the link 35 is in engagement with the horizontal extension 16 of the catch 14, such engagement being maintained by the spring 18. Obviously the sliding door cannot be opened thus from the left side of the elevator shaft. To open the door, the operator swings the arm 21 of the actuating lever 19 in the direction of the arrow shown in Fig. 2 of the drawings, thereby disengaging the catch 14 from the link 35. As soon as this disengagement takes place, the door 10 can be shifted to its open position, the links 35 and 38 then approaching each other, and the door closing means moving in an arc-shaped path until its lug 68 abuts against the outer end 69 of the slot 67. In the meantime the wedge-shaped end 37 of the link 35 is shifted around its pivot 36 and is seated in the notch 31. When the door reaches its fully open position, the tumbler 28 has been shifted by the link 35 around its pivot 29, thereby bringing the notch 31 into registering position with the lug 25 upon the lever 19, the spring 26 then seating the said lug in the said notch, thus preventing a disengagement of the link 35 from the tumbler 28, whereby the door is held locked in its open position.

In order to close the door, the operator

shifts by the intermediary of the rod 23 the arm 21 of the lever 19 in a direction opposite to the arrow shown in Fig. 2 of the drawings, thereby releasing the tumbler 28. 5 The spring 54 of the door closing means, which has been in opening the door compressed, is thus rendered operative, causing the links 35 and 38 to move away from each other with the result that the door is moved 10 toward its closing position. The end 37 of the link 35 is thus disengaged from the tumbler, and the latter shifted until the edge 33 of its recess 32 abuts against the stop 27. The wedge-shaped end 37 of the link 35 rides 15 over the rounded edge 17 of the extension 16 of the catch 14, and is brought into the position shown in Fig. 2 of the drawings. The mechanism in the liquid chamber of the door closing means prevents a slamming of the 20 door. While the door is moving toward its open position, the piston 55 moves in the direction of the arrow shown in Fig. 4 of the drawings, liquid being freely admitted from the front of the piston to the rear of 25 the same. When, however, the door is closed by the action of the spring 54, the valve 59 covers the port 58 and the liquid is forced from the front of the piston to the rear of the same through the passage 61, slamming 30 being prevented by the resistance of the liquid to the operation of the piston.

A modification of the invention is shown in Figs. 8 and 9 of the drawings, differing from the one above described in that the 35 door closing device lacks the means which prevents the slamming of the door, or in other words the casing 41 lacks the liquid chamber and the means located therein; otherwise the construction of the device is 40 the same, its operation being also identical with the one above described. This modification is specially adapted for use in connection with heavy doors.

While herein a stationary door 11 has 45 been described, to which the link 38 is fastened by the intermediary of the bracket 40, it is obvious that the invention may be applied to sliding-doors which are not combined with stationary doors. In the latter 50 case the bracket 40 is obviously fastened to the wall of the elevator shaft or to the door frame.

What I claim is:—

1. In a device of the character described, 55 the combination with a door frame and a sliding door, of a link pivoted to said door, a link fulcrumed to said frame, means connecting said two links tending in all positions of said door to move the latter into closing position, and a locking member mounted upon said door for locking said links against motion. 60

2. In a device of the character described, 65 the combination with a door frame and a sliding door, of a link pivoted to said door,

a link fulcrumed to said frame, means connecting said two links tending in all positions of said door to move the latter into closing position, and a locking member mounted upon said door adapted to engage 70 the link pivoted to said door and to hold the latter in its closed position.

3. In a device of the character described, the combination with a door frame and a sliding door, of a link pivoted to said door, 75 a link fulcrumed to said frame, means connecting said two links tending to move said door into closing position, a locking member mounted upon said door adapted to engage the link pivoted to said door and to hold the latter in its closed position, and means adapted to engage said late named link when the door is in its open position to lock it therein.

4. In a device of the character described, 80 the combination with a door frame and a sliding door, of a link pivoted to said door, a link fulcrumed to said frame, means connecting said two links tending to move said door into closing position, a locking member 85 mounted upon said door adapted to engage the link upon said door and to hold thereby the latter in closing position, means for disengaging said locking member from said last named link to move said door to open 90 position, and means upon said door adapted to engage the link thereon for automatically locking said links against motion when said door is in its open position.

5. In a device of the character described, 100 the combination with a door frame and a sliding door, of means connecting said two elements tending to move said door into closing position, and a locking means upon said door adapted to engage said first named 105 means for locking the latter against motion when said door is both in its fully open and closed positions.

6. In a device of the character described, 110 the combination with a door frame and a sliding door, of a link pivoted to said door, a link fulcrumed to said frame, means connecting said two links tending to move said door into closing position, a lock casing 115 mounted upon said door having an aperture through which the link pivoted to said door projects, a spring pressed catch in said casing adapted to engage the link projecting into the same for holding the latter in closing position, a lever in said casing adapted 120 to disengage said catch from said link, said lever being provided with a lug, and a rotary tumbler having two recesses, one of the same being adapted to be engaged by the link upon said door and the other by said 125 lug when the door is in its open position, whereby said links are locked against closing movement.

7. In a device of the character described, 130 the combination with a door frame and a

sliding door, of means connecting said two elements tending to move said door into closing position, locking means mounted upon said door for locking said first named means against motion when said door is both in its fully open and closed positions, and means for guiding the motion of said door closing means.

8. In a device of the character described, 10 the combination with a door frame and a sliding door, of a link pivoted to said door, a link fulcrumed to said door frame, means connecting said two links tending to move

said door into closing position, a locking member mounted upon said door for locking 15 said links against motion, and means for retarding the closing movement of said first mentioned means.

Signed at New York, in the county of New York, and State of New York, this 14th 20 day of October, A. D. 1913.

JACOB KOHN.
